UNITED STATES PATENT OFFICE.

LOUIS COATALEN, OF WOLVERHAMPTON, ENGLAND, ASSIGNOR OF ONE-HALF TO
SUNBEAM MOTOR CAR COMPANY LIMITED, OF WOLVERHAMPTON, ENGLAND.

COOLING INTERNAL-COMBUSTION ENGINES.

1,299,129.

Specification of Letters Patent.

Patented Apr. 1, 1919.

Application filed May 23, 1917. Serial No. 170,540.

To all whom it may concern:

Be it known that I, LOUIS COATALEN, a subject of the King of England, residing in Wolverhampton, Staffordshire, England, 5 have invented certain new and useful Improvements in Cooling Internal-Combustion Engines, of which the following is a specification.

This invention has for its object to improve 10 the cooling of the interior of internal combustion engines, particularly such as are used on aeroplanes and the like. It has previously been proposed to pass air through the crank chamber, and it is the object of this 15 invention to provide a system of this kind for engines having a cam shaft arranged above the cylinder.

According to this invention, air is admitted at the end of the crank chamber opposite to that at which the cam shaft drive is arranged and the air passing along the crank chamber is then caused to travel up the cam shaft gear casing preferably after having passed through a centrifugal separator or filter. Thus the oil picked up by the 20 air passing along the crank chamber is not carried up the cam shaft gear casing. At the top of the casing there are provided one or more outlets, preferably with a cowl or 25 ventilator projecting in the opposite direction to the air draft.

The accompanying drawing shows in side elevation more or less diagrammatically a four cylinder engine provided with a reducing gear through which the propeller is driven and to which this invention has been applied.

The crank chamber is indicated at A and this contains a longitudinal crank shaft supported in bearings in any suitable manner. The cylinders are indicated at B and inside a casing C is a cam shaft the axis of which is indicated at D. This cam shaft is driven by gearing of any suitable kind located in the casing E and driven from the crank shaft, the axis of which is at F. The crank shaft also drives through a reducing gear on to the propeller shaft G the reducing gear being located in the housing H. This housing is provided with an air funnel J causing air to pass in the direction of the arrows downward into the crank case. Further, the

propeller shaft G may be hollow and air may enter this in the direction of the arrows and if desired the crank chamber may be 55 provided with one or more air inlets K. The air entering in this manner travels along the crank chamber, up the casing E, and out through the outlet funnel L. At the bottom of the casing E may be a filter or filters of any suitable kind, or some known form of centrifugal separator may be used to separate the particles of oil from the air. Alternatively the filters or filtering devices may be located at the top of the casing. 60 65

It will be noticed that the air inlets are located behind the propeller, the blades of which are shown at N, so that the air is forced into the crank case under a slight pressure, but if desired any suitable fan or 70 fans may be used.

What I claim as my invention and desire to secure by Letters Patent is:—

1. In an internal combustion engine for use in aerial machines, a crank casing having 75 holes therein, a casing projecting upwardly from said crank casing and containing the gear driving the overhead cam shaft and means for causing air to pass through the holes and out through the top of the upwardly projecting casing. 80

2. In an internal combustion engine for use in aerial machines, a crank shaft, a propeller driven by the crank shaft, a casing for the crank shaft, an air funnel on the 85 casing in proximity to the propeller, an overhead cam shaft, a casing projecting upwardly from the crank casing and containing the gear for driving the overhead cam shaft and at the opposite end of the crank casing to the propeller and a funnel on the gear casing, for the purpose described. 90

3. In an internal combustion engine for use in aerial machines, a crank shaft, a propeller driven by the crank shaft, a hollow propeller shaft, a casing for the crank shaft, an air funnel on the casing in proximity to the propeller, an overhead cam shaft, a casing projecting upwardly from the crank casing and containing the gear for driving 100 the overhead cam shaft and at the opposite end of the crank casing to the propeller and a funnel on the gear casing, for the purpose described. 95

4. In an internal combustion engine for use in aerial machines, a crank shaft, a propeller driven by the crank shaft, a casing for the crank shaft, an air funnel on the casing 5 in proximity to the propeller, an overhead cam shaft, a casing projecting upwardly from the crank casing and containing the gear for driving the overhead cam shaft and at the opposite end of the crank casing to 10 the propeller, an oil separator at the bottom

of the gear casing and a funnel on the gear casing, for the purpose described.

In testimony whereof I have signed my name to this specification in the presence of two subscribing witnesses.

LOUIS COATALEN.
